UNITED STATES PATENT OFFICE.

WILLIAM A. TURBAYNE, OF NIAGARA FALLS, NEW YORK, ASSIGNOR TO U. S. LIGHT & HEAT CORPORATION, OF NIAGARA FALLS, NEW YORK, A CORPORATION OF NEW YORK.

VARIABLE-SPEED CONSTANT-VOLTAGE GENERATOR.

1,382,257.

Specification of Letters Patent. Patented June 21, 1921.

Application filed November 6, 1916. Serial No. 129,669.

To all whom it may concern:

Be it known that I, WILLIAM A. TURBAYNE, a citizen of the United States, residing at Niagara Falls, in the county of 5 Niagara and State of New York, have invented new and useful Improvements in Variable-Speed Constant-Voltage Generators, of which the following is a specification.

The present invention relates to variable 10 speed constant voltage generators.

Many devices are in use for maintaining substantially constant the voltage developed at the terminals of a generator which is subjected to wide variations in speed. The 15 present invention relates to generators which are inherently capable of delivering a substantially constant voltage, no extraneous devices being necessary.

An object of the present invention is to 20 provide a novel dynamo-electric machine which, when operated as a generator, will inherently develop a substantially constant voltage.

A further object is to provide a dynamo- 25 electric machine of the kind referred to, which will be simple in construction and cheap to manufacture.

Further objects will be apparent as the 30 description proceeds.

Referring to the drawings:

Figure 1 represents diagrammatically one 35 embodiment of the invention.

Fig. 2 represents a development of the 40 armature windings showing the field poles, the brushes and the field windings co-operating therewith.

Figs. 3 and 4 represent details.

The field frame of the dynamo-electric 45 machine which forms the subject-matter of the present invention, is indicated as a whole by the numeral 1. This field frame 1 is represented as the stator of the machine.

In the embodiment illustrated, the armature is designed to rotate. This armature 50 is indicated as a whole by the numeral 2.

The field frame, as illustrated, is provided with six pole pieces, 3, 4, 5, 6, 7 and 8. These pole pieces are provided with field windings 3^a, 4^a, 5^a, 6^b, 7^b, and 8^b respectively.

55 Located adjacent to each of the pole pieces 3 to 8 inclusive are auxiliary pole pieces 9, 10, 11, 12, 13 and 14. These auxiliary pole pieces 9 to 14 inclusive, are disposed a short distance from the main pole pieces 3 to 8 inclusive, in the direction of rotation of the

armature 2. The auxiliary pole pieces are provided with windings 9^c, 10^c, 11^c, 12^c, 13^c, and 14^c respectively.

The armature 2 is provided with a commutator 15. Bearing on the commutator 15 are six brushes 16, 17, 18, 19, 20 and 21. Of these brushes 16 and 20 bear on the commutator at points of equal potential. Said brushes 16 and 20 are connected together and to the lead 22 of the generator. Brushes 17 and 19 also bear on the commutator at points of equal potential and are connected together and to the lead 23 of the generator. Brushes 16 and 20 on the one hand and brushes 17 and 19 on the other hand, constitute the main brushes of the machine. Using a series two-path armature with symmetrical end connections, considering only the flux from the main poles and disregarding armature cross flux, the points of maximum difference of potential will come opposite the main pole pieces. Therefore, brushes 16 and 20 will be located opposite the centers of pole pieces 5 and 7, while brushes 17 and 19 will be located opposite the centers of pole pieces 4 and 8. Brushes 18 and 21 are auxiliary brushes located at points displaced from the center line through the pole pieces 3 and 6 by an amount equal to the angle X which will be chosen of a magnitude best suited for the regulation desired.

Referring to Fig. 1, it will be noted that the field windings 3^a, 4^a, 5^a are connected across the main positive brushes 16 and 20 and the auxiliary brush 18. Field windings 6^b, 7^b and 8^b are connected across negative brushes 17 and 19 and auxiliary brush 21. The auxiliary windings 9^c, 10^c, 11^c, 12^c, 13^c, and 14^c are preferably connected to the auxiliary brushes 18 and 21 as indicated. The field rheostat 24 may be provided in series with the field windings 9^c to 14^c inclusive.

The complete circuit arrangements of the dynamo electric machine are illustrated in Fig. 2, which shows the direction of current in the armature conductors. The lowermost arrows illustrate the presence and direction of field exciting current. The uppermost arrows indicate the presence and direction of load current in the armature conductors when circuit is completed across leads 22 and 23. In Fig. 2, windings 3^a, 4^a, and 5^a have been indicated as a single coil marked A. Windings 6^b, 7^b, and 8^b have been indi- 110

cated as a single coil marked B. The auxiliary windings, 9°, 10°, 11°, 12°, 13°, and 14° have been indicated as a single coil marked C. The solid line curve under the commutator represents the distribution of voltage around the commutator with the main poles only excited and the armature on open circuit. The broken line curve indicates the shifted position of the voltage curve in the direction of rotation, with the auxiliary poles excited. For purposes of explanation, it has been assumed that the generator is designed to maintain 65 volts at its terminals.

15 The main brushes 16 and 20 and 17 and 19 are at points of maximum potential difference when the main poles only are excited and, as will be noted in Fig. 2, are located to commute armature conductors located 20 substantially midway between adjacent main poles. Under this condition, a difference of potential of some 15 volts exists across brushes 16 and 18 and brushes 19 and 21, across which the main field windings are 25 connected, so that current through the left hand main field windings will flow from brush 16 to 18, while current in the left hand main field windings will flow from brush 21 to brush 19, the direction of this 30 current around the various field poles giving them the polarity indicated on the drawings. Under this condition also, the auxiliary shunt field winding connected across brushes 18 and 21 will be subjected to a difference of 35 potential of some 35 volts, current flowing in the direction from positive brush 18 to negative brush 21 and giving the auxiliary poles 9 to 14 inclusive the polarities indicated on the drawing. The excitation of 40 these auxiliary poles, however, will tend to alter the distribution of voltage around the commutator, shifting the curve to the right. This shifting tendency will increase as the voltage across brushes 18 and 21 increases,— 45 following speed increases, for instance.

Under the conditions illustrated by the broken line curve in Fig. 2, it will be noted that the difference of potential existing across brushes 16 and 18 and 21 and 19, has 50 become reduced, so that substantially only 3 volts exists across these brushes, which means a very decided reduction in the current through the main field windings. Under this condition also, the voltage across 55 brushes 18 and 21 will have risen to some 55 volts. It is obvious from the diagram that the voltage across brushes 18 and 21 could not greatly exceed this value, as otherwise the current through the main field windings 60 would drop to zero and the machine would be incapable of producing the desired E. M. F. The most advantageous position for the auxiliary brushes 18 and 21 will be determined in practice. The maximum value of 65 the voltage developed would be determined

by adjustment of the field rheostat 24 connected in circuit with the auxiliary windings.

In the foregoing explanation of the operation of the machine, reference to the armature cross flux has been omitted for the sake of simplicity. The present invention contemplates means whereby the effects of the armature current shall be compensated for so that the shifting of the field flux will be 75 uninfluenced by this armature current, the flux distortion being brought about wholly by the action of the auxiliary poles. It is well known, of course, that the effects of the armature current can be absolutely compensated for by means of compensating windings of the well known Ryan type distributed around the pole faces and connected in series with the external circuit. These compensating windings exert a magneto-motive force exactly equal to the M. M. F. imparted by the armature winding. The particular construction of field frame illustrated in connection with the described embodiment of this invention, adapts itself 85 readily to a less expensive means for compensating for the affects of the armature current. Such means are illustrated in the detail views, Figs. 3 and 4. In Fig. 3, main pole 3 is illustrated having in addition to 90 the main exciting winding 3^a, the series windings 25, which are adapted to be connected in the external circuit. The windings 25 will be given such a value that any tendency of the armature current to distort the 95 flux and thereby raise the voltage on brushes 18 and 21, will be offset by the increased excitation applied to the main poles.

A similar result may be obtained by the means illustrated in Fig. 4. In this figure 105 the series windings 25, also adapted to be connected in the external load circuit, are applied to the auxiliary poles, the current in this case flowing around these auxiliary poles in a direction opposite to that flowing 110 in the shunt winding. The current around these auxiliary poles, therefore, exert a M. M. F. opposed to that developed by the current in the armature windings.

The embodiments of the present invention 115 which have been described, are chosen only for the purpose of illustration and are not to be considered in any limiting sense. Many modifications will occur to those skilled in the art. It is desired to cover in 120 the patent all such modifications that fall within the scope of the invention as defined by the appended claims.

What I claim as new and desire to secure by Letters Patent of the United States is:— 125

1. In a variable speed generator, means for providing field flux, an armature, main brushes coöoperating with said armature, auxiliary brushes coöoperating with said main brushes to supply current for energiz- 130

ing said means, and means responsive to the voltage across said auxiliary brushes for distorting the flux due to said first mentioned means.

5. 2. In a variable speed generator, means for providing field flux, an armature, main brushes coöperating with said armature, auxiliary brushes coöperating with said main brushes to supply current for energizing said means, means for opposing armature cross flux and voltage responsive means for distorting the flux of said field flux-providing means.

10. 3. In a variable speed generator, field poles and an armature, main brushes co-operating with said armature to commutate armature conductors placed substantially midway between adjacent poles, a pair of auxiliary brushes, each coöperating with a main brush to provide excitation for said field poles, and means responsive to the E. M. F. across said auxiliary brushes for shifting the points of maximum potential.

15. 4. In a variable speed generator, field poles and an armature, main brushes co-operating with said armature, a pair of auxiliary brushes each coöperating with a main brush to provide excitation for said field poles, and means responsive to the E. M. F. across said auxiliary brushes for distorting the flux due to said field poles.

20. 5. In a variable speed generator, field poles and an armature, main brushes co-operating with said armature, a pair of auxiliary brushes each coöperating with a main brush to provide excitation for said field poles, and means responsive to the E. M. F. across said auxiliary brushes for distorting the flux due to said field poles.

25. 6. In a variable speed generator, field poles for providing field flux, an armature, main brushes commutating armature conductors placed substantially midway between adjacent poles, auxiliary brushes offset from said main brushes, a set of field windings for exciting said poles connected between each main brush and an auxiliary

brush, and means responsive to the E. M. F. across said auxiliary brushes for distorting 50 said field flux.

7. In a variable speed generator, field poles for providing field flux, an armature, main brushes commutating armature conductors located substantially midway between said field poles, auxiliary brushes offset from said main brushes, a set of field windings for exciting said poles connected between each main brush and an auxiliary brush, and means responsive to the E. M. F. 60 across said auxiliary brushes for shifting the flux due to said poles.

8. In a variable speed generator, an armature, a main brush and an auxiliary brush, field windings connected between said 65 brushes, a second main brush and a second auxiliary brush, other field windings connected between said second brushes, and means responsive to the E. M. F. across said auxiliary brushes for distorting the flux 70 due to said field windings to vary the potential difference between each main brush and its coöperating auxiliary brush.

9. In a variable speed generator, in combination, means for providing field flux, 75 an armature, main brushes, auxiliary brushes, said means being responsive to the potential difference between said main and auxiliary brushes, and means connected across said auxiliary brushes for distorting 80 the flux due to said first mentioned means.

10. In a variable speed generator, means for providing field flux, an armature, main brushes coöperating with said armature, auxiliary brushes, two sets of field windings, 85 each set being connected between an auxiliary brush and a main brush, means for opposing armature cross-flux and means responsive to the voltage across said auxiliary brushes for distorting the flux due to said 90 field windings to vary the difference of potential between each main brush and its corresponding auxiliary brush.

In witness whereof, I have hereunto subscribed my name.

WILLIAM A. TURBAYNE.
